SECURING DEVICE FOR CONNECTING FLEXIBLE MEMBERS TOGETHER

Fred M. Lund and John H. Lund, Chicago, Ill.

Application February 7, 1940, Serial No. 317,624

7 Claims. (Cl. 24—265)

The invention relates generally to securing devices and more particularly to devices of this nature which are especially adapted for releasably connecting or joining the flexible straps, cords or similar supporting means for wrist watches or the like.

An object of the invention is to provide new and improved means of this nature which is simple in construction, affords a convenient adjustment of the circumferential dimension of the supporting means, is quickly releasable and when released permits of instant increase in such dimension to allow the assembly to be removed, and which cannot become accidentally disengaged.

Another object is to provide a new and improved securing means whereby the overlapping ends of flexible connecting means, such as oppositely extending cords on a wrist watch or like article, are fastened to intermediate portions of the opposite connecting means in such manner that the article may be conveniently attached or removed.

Other objects and advantages, inherent in the structure embodying the invention, will become apparent in the description and from the accompanying drawing, in which:

Figure 1 is a view in perspective of a securing device embodying the features of the invention, the device being shown in closed or securing condition.

Fig. 2 is a view similar to Fig. 1 showing the device in the initial stage of its release and illustrating a modified form of design.

Fig. 3 is a view similar to Fig. 1 showing the device in its open or release position.

Figs. 4 and 5 are views on an enlarged scale showing the abutting faces of the sections of the separable connecting member.

Figs. 6 and 8 illustrate the manner in which the separable sections are joined and show successive steps in making the connection.

Fig. 7 is a side view of the other connecting member.

The embodiment of the invention which has been selected for illustrative purposes has been shown and will be described in connection with the means by which a wrist watch is releasably secured about the wrist of the wearer. This means, sometimes loosely termed the "strap," is as shown of a type which has recently become popular and comprises single cords 11, 12 secured one to each end of the wrist watch case by suitable securing means 13. The cords are of sufficient length to permit the free ends thereof

to be brought into overlapping relation on the side of the wrist opposite the watch.

For convenience, we will refer to the article which is supported as a watch and to the flexible supporting members as cords, but it is to be understood that we do so by way of explanation, not limitation, since the present invention is well adapted for use in connection with other articles or supporting means.

- 10 Each of the free ends of the cords 11, 12 has secured thereto one part or section of a connecting member which, through another complementary section, is adjustably secured or connected to an intermediate portion of the other cord. The connecting members are so arranged that the cords may be drawn taut about the wearer's wrist, or by a simple manipulation be freed for movement to vary the circumferential dimension of the cords. Moreover, the connecting members cooperate in maintaining each other against accidental release.

In the drawing, the connecting members are generally designated by the numerals 14 and 15, and reference will first be had to the illustrated structure of the right-hand member 15. This member includes a tubular shell 16 forming one section of the connector and a second tubular shell 17 constituting the other section thereof. The section 16 has a closed end 18 and the opposite end 19 is adapted to receive the free end of the cord 11. Suitable means (not shown) is provided for securing the cord permanently to the section 16. The other section 17 is tubular and slidably encircles an intermediate portion 35 of the length of the cord 12. In the present instance, the sections are pivotally connected for swinging movement between a closed or adjacent position, as shown in Fig. 1, and an open separated position, as shown in Fig. 3, and the 40 location of the pivot is preferably such that a lateral pull on the end of the cord 12 will swing the sections from their closed to their open relationship. As shown in Fig. 7, the pivotal connection is effected by providing spaced apertures in the inner and end walls of the section 16 to provide a pintle 21 for engagement by a curl 22 on the section 17. In Fig. 2 the section 17 carries spaced ears 20 between which the pintle is supported for engagement by a curl or the 45 like.

The casing sections are provided with cooperating means for clamping the section 17 to its associated cord 12 whenever the sections 16 and 17 are closed. Thus, referring to Figs. 3 and 7, the adjacent or meeting face 23 of the section 16 has

an outstanding headed pin 24, or the like, secured to a central portion thereof. The pin is arranged to extend through an aperture 25 in the opposed or meeting face 26 of the section 17 and bindingly engage the cord 12 when the sections are closed. Hence, when the sections are open, the section 17 may slide freely along the length of the cord 12, which movement is prevented when the sections are closed. If desired, a catch finger 27 on one of the sections, in this instance the section 16, may frictionally engage a complementary notch or recess 28 in the section 17 to provide a friction latch for holding the sections in their closed relation.

The other connecting member 14 includes a pair of separable sections 29 and 30. The section 30 resembles the section 16 of the other connecting member 15 in that it is tubular, has a closed end 31 and an open end 32 to receive the free end of the cord 12 which is fixed therein by suitable securing means (not shown). The other section 29 is also a tubular member resembling the section 17 in that it is mounted for sliding movement along the length of the cord 11. The section 29 carries means by which it may be clamped at various positions of adjustment along the length of the cord 11. Thus, as shown in Fig. 4, outstanding bosses 33 support therebetween a bell crank lever having an elongated operating arm 34 and a short arm 35 which extends through a suitable aperture in the wall of the section into binding engagement with the cord 11. It is preferred that the arm 34 be of sufficient length to extend beyond an end of the section for convenience in the manipulation thereof, and to avoid the possibility that a finger nail will be broken in the manipulation of the lever. If desired, such means as a finger 36 (Fig. 2) having a nib 36^a may be provided on the section 29 to extend to a position where in assembly the nib may frictionally engage an aperture in a wall of the section 30 to maintain the sections against accidental separation.

The sections 29 and 30 have cooperating means for connecting the sections together. Thus, the abutting or meeting face 37 of the section 29 has an outstanding pin 38 thereon provided with diametrically opposed lateral projections 39. The meeting face 40 (Fig. 5) of the section 30 has an aperture 41 therein which in outline is complementary to the contour of the pin 38 and projections 39. However, as will be noted from a comparison of Figs. 4 and 5, the aperture 41 and the pin and projections 38, 39 have an angular relation necessitating the insertion of the pin and projections into the aperture while the sections 29 and 30 are angularly related as shown in Fig. 6. Following such insertion, relative rotation of the sections substantially in the plane of their meeting faces to bring them into registering abutment disposes the sections in operative connected relation and engages the nib 36^a with its cooperating aperture.

In operation, and prior to placing the assembly about a wearer's wrist, the sections 29 and 30 are disconnected and the sections 16 and 17 are open as shown in Fig. 3. The section 17 is slideable with respect to the cord 12 and may be moved toward the free end of the cord until it is stopped by abutment with the section 30 of the other connecting member. This expands or opens the loop to permit it to pass freely over the wearer's hand. Thereafter, the wearer by grasping the section 30 may pull the cord 12 through the section 17 until the desired degree of tautness is obtained, whereupon closing of the sections 16

and 17 will secure the parts in this relation. Initially, it will be necessary to adjust the section 29 to a proper position along the length of the cord 11 and to secure it in this position. The location of the section 29 is such that when the connecting member 15 is closed to maintain the cords taut, as desired, the connection of the sections 29 and 30 will hold the portions of the cords between the connecting members 14 and 15, and particularly the end portion of the cord 12, under slight tension. The degree of tension in a properly adjusted device will be such that relative rotational movement of the sections 29 and 30 to a position in which they might become accidentally disconnected is restrained. Thus, the present connecting means permits of instant adjustment of the circumferential dimension of the cords and provides a secure connection between the overlapping ends of the cords, which, being in effect a double union, is not susceptible of accidental disengagement. To remove the assembly, it is only necessary for the user relatively to rotate the sections 29 and 30 to permit disconnection thereof. Once separated, a lateral or sidewise pull by the user on the free end of the cord 12 will open the casing sections 16 and 17, thereby freeing the cord 12 for sliding movement relative to the section 17. As may be seen in Figs. 1, 3 and 7, the wall 26^a of the section 17 that is opposite to the meeting face 26 is preferably formed to provide a convex surface over which the cord rides in its sliding movement through the section. This convex surface may be fashioned by smoothly distorting the mouth portions of the wall 26^a outwardly. This convex surface insures that the cord will slip freely through the section since the mouths of the cord receiving bore are substantially larger than the cord. Moreover, the convex surface facilitates movement of the cord through the section when the user pulls on the free end of the cord 12 to tighten the assembly even though the direction of pull on the cord end is in a direction sharply angular to the rest of the cord.

It may be mentioned that there is no structural difference between the securing means shown in Fig. 1 and that shown in Fig. 2. The connecting means of Fig. 1 has sections which are elongated, substantially square tubes designed to simulate the appearance of the strands of a rope. In the modified design shown in Fig. 2, the sections are semicircular disks which, when the sections are closed or joined, form circular disks. The bore through the section 17 has an internal convex wall similar to the wall 26^a on the device shown in Fig. 1. It will be evident that the design of the connecting means may take many forms other than the two herein illustrated.

While the invention is susceptible of various modifications and alternative constructions, we have shown in the drawing and have herein described in detail the preferred embodiment, but it is to be understood that we do not thereby intend to limit the invention to the specific form disclosed, but intend to cover all modifications and alternative constructions falling within the spirit and scope of the invention as expressed in the appended claims.

We claim as our invention:

1. Securing means of the character described comprising, in combination, a pair of flexible members having end portions arranged to be placed in substantially side by side relation, a first connector means slidably mounted on one

member inwardly of its end, a second connector means adjustably secured to the other member inwardly of the end thereof, and means on the end of each member for connecting such end with the connector means on the opposite member, the end means which cooperates with the slidable connector means including means for restraining said connector means against sliding movement.

2. In a device for detachably securing the overlapping ends of flexible cords or the like together, the combination of a member having a section secured to the end of one cord and having another section adjustable along the length of the other cord, means for detachably securing said sections in an adjacent relationship, means for preventing said adjustable movement when said sections are adjacent, a pair of separable members respectively secured to the end of said other cord and slidable on said one cord, means for clamping the slidable separable member adjustably to its associated cord, and means for detachably connecting said separable members.

3. In a device for detachably securing the overlapping ends of flexible cords or the like together, the combination of a pair of pivotally joined members respectively secured to the end of a first cord and slidable along the other cord, means for releasably securing said members in an adjacent relationship, means for preventing such sliding movement when said members are adjacent, a pair of separable members respectively secured to the end of said other cord and slidable on said first cord, means for clamping the slidable separable member adjustably to its associated cord, and means for detachably connecting said separable members, the releasable securing means for said pivotally joined members being releasable by a pull on the end of said other cord when the separable members are disconnected to free the pivotally joined member for sliding movement along said other cord.

4. In a device for detachably securing the overlapping ends of flexible cords or the like together, the combination of means at the ends of said overlapping cords for connecting the ends to intermediate portions of the other cords including a pair of pivotally joined members respectively secured to the end of one cord and slidably mounted on the other cord, means for detachably securing said members in an adjacent relationship, means for preventing such sliding movement when said members are adjacent, a pair of separable members respectively secured to the end of said other cord and slidable on said one cord, means for clamping the slidable separable member adjustably to its associated cord, and means for detachably connecting said separable members by relative rotational movement, the holding tension on said cords being exerted to maintain the separable members against disconnection.

5. In a device for detachably securing the over-

lapping ends of flexible cords or the like together, the combination of a pair of pivotally joined coacting sections, means for securing one of said sections to the end portion of a first cord, the other of said sections having a bore therein through which the other cord slidably extends, means for detachably securing said sections in an adjacent relationship including means for preventing sliding movement of said other cord through said bore when the sections are adjacent, said bore having a substantially rounded internal surface facilitating sliding movement of said cord through said section, and means for securing the end of said other cord to an intermediate portion of said one cord.

6. Securing means of the character described comprising, in combination, a pair of flexible members having end portions arranged to be placed in substantially side by side relation, a first connector means slidably mounted on one member inwardly of its end, a second connector means permanently mounted for sliding movement on the other member inwardly of the end thereof, means for securing said second connector means in a fixed position on said other member, a third connector means fixed on the end of said one member for detachably connecting such end with the second connector, and a fourth connector fixed on the end of said other member for connecting said last mentioned end with said first connector and including means for restraining said first connector against sliding movement.

7. In a device for detachably securing the overlapping ends of flexible wrist cords or the like together, the combination of a pair of clasps comprising respectively a pair of similar hinged cooperating sections and a pair of similar separable cooperating sections, said hinged sections being respectively secured to the end of one cord and slidably mounted on the other cord, one of said separable sections being permanently mounted for sliding movement on said one cord and including means for adjustably securing it in a fixed predetermined position thereon effective to hold the cord tensioned on the wearer's wrist after said clasps have been secured, the other of said separable sections being secured to the end of said other cord and including easily securable means for attachment to said one section, said other section being of a convenient size adapted to be grasped between the thumb and fingers of the wearer and moved against the tension of the cord into a position for attachment, means for detachably securing said hinged sections in an adjacent relationship, and means for preventing movement of the slidably hinged section on said other cord when said hinged sections are adjacent whereby to hold said separable sections against accidental detachment.
